E. J. ČAPEK.

DISINFECTOR AND DEODORIZER,
APPLICATION FILED FEB. 16, 1917.

1,242,321.

Patented Oct. 9, 1917.

Inventor

E. J. ČAPEK

By Watson E. Coleman

Attorney

UNITED STATES PATENT OFFICE.

ERNEST J. ČAPEK, OF SCHUYLER, NEBRASKA.

DISINFECTOR AND DEODORIZER.

1,242,321.

Specification of Letters Patent.

Patented Oct. 9, 1917.

Application filed February 16, 1917. Serial No. 149,052.

To all whom it may concern:

Be it known that Doctor ERNEST J. ČAPEK, a physician and surgeon, who has made application to become a citizen of the United States, residing at Schuyler, in the county of Colfax and State of Nebraska, has invented certain new and useful Improvements in Disinfectors and Deodorizers, of which the following is a specification, reference being had to the accompanying drawings.

This invention relates to disinfecting and fumigating apparatus, and particularly to devices for disinfecting and fumigating articles such as clothes by the use of formaldehyde, or other like disinfecting materials.

The general object of my invention is the provision of an extremely simple fumigating and disinfecting apparatus having few parts and which is very cheaply made and which requires very simple manipulation and which would yet be thoroughly efficient in action.

A further object of the invention is to provide means whereby the clothes or other articles intended to be disinfected may be supported within the disinfecting chamber, out of contact with formaldehyde or other solutions operating therein.

Still another object is to provide means whereby after the clothes or other articles have been disinfected for a certain length of time by the means of one solution, additional chemicals may be added in order to deodorize the clothes and this without the necessity of removing the clothes from the disinfecter or removing the disinfecting material itself.

Other objects will appear in the course of the following description.

My invention is illustrated in the accompanying drawings, in which:

Figure 1 is a vertical sectional view of a disinfecter constructed in accordance with my invention;

Fig. 2 is a fragmentary section on the line 2-2 of Fig. 1 looking toward the lid;

Fig. 3 is a top plan view of the drum, the chimney 20 and the tube 21 being in section; and

Fig. 4 is an elevation of the pouring tube.

Referring to these figures, 10 designates the body of the disinfecting apparatus or container. This is made preferably of galvanized iron or like material and in ordinary

practice will be about 18 inches in diameter and 26 inches in height. Preferably there is

disposed in this bottom container 10, a false bottom 11 of wood or other non-heat conducting material which is to be readily removable from the container. The bottom of 60 the container is provided with strips 12 of metal, disposed in cruciform relation and extending out beyond the sides of the container and these extensions of these strips are connected to the side wall of the container by means of angle irons 13 or in any other suitable manner to make them sufficiently rigid. These projecting ends of the strips 12 and the angle irons 13 form foot 65 pieces, as will hereafter more fully appear. 70

For the purpose of closing in the top of the container I provide a lid 14, which is likewise preferably made of galvanized iron and provided with handles 15, this lid having an exterior downwardly extending 75 flange 16, about four inches in depth and an interior downwardly extending flange 17 of the same depth. These flanges 16 and 17 are formed in concentric relation and so close together as to tightly engage the side 80 wall of the container 10, when the lid is in place. The space between the flanges 16 and 17 is about four inches in depth and this space is about half filled with asbestos, or other packing, designated at 18. It will 85 thus be seen that as the lid is forced down upon the container, a gas tight joint is formed between the upper container and the lid.

Adapted to be used in connection with the 90 container 10 is a drum 19, open at its bottom, and having a side wall and a top wall. The side wall and the top wall are perforated. The drum is formed with a central 95 opening in its top and from this central opening extends upward a column or chimney 20, which is likewise perforated. This column or chimney is preferably about four inches in diameter and is perforated. The combined height of the drum 19 and the 100 column 20 is slightly less than the height of the container 10 with the lid in place, so that when the lid is closed the upper end of the chimney 20 is spaced a short distance from the lid. Adapted to be disposed within the chimney 20 is a funnel tube 21 of about the same length as the chimney and formed at its upper end with the funnel 22, which is adapted to rest upon the upper end of the chimney. 105

Used in connection with the disinfecting apparatus above described and forming part 110

thereof is a pan 23, which in use rests upon the non-heat conducting bottom 11 and disposed in this pan is a heating means, such for instance, as an ordinary tea kettle 24 having a lid 25.

5 In the actual use of the invention the tea kettle, or container 24, wherein water is vigorously boiling, is disposed within the pan 23, the spout of the tea kettle having been previously closed by a wad of cotton. 10 The drum 19 is then immediately placed over the tea kettle and the pan 23 and then the clothes to be disinfected are piled into the container over the drum 19 and around 15 the chimney 20. The clothing is, of course, placed sufficiently loosely so that the generated gas or vapor may have ready access to all parts of the clothing. This procedure is to be executed as quickly as possible so 20 as to prevent a cooling off of the water in the tea kettle. The formalin solution to any quantity desired, as for instance two ounces, is poured through the funnel 22 and runs downward over the top of the tea 25 kettle into the underlying pan 23. Without any delay the lid is closed as tight as possible and to this end the operator should apply the whole weight of his body on the lid and move around the lid so as to force 30 all parts of the lid securely down into contact with the container. During this operation of closing the lid the operator should hold the container from movement by treading on the outwardly projecting portions of 35 the angle irons 13, thus holding the container rigid. The formaldehyde generated by the heat acting on the formalin solution is enabled to reach the clothes containing space through the perforations of the drum 40 and chimney. After twelve or twenty-four hours or any other suitable length of time, the lid is removed and strong ammonia water to the amount of four ounces or so is poured through the funnel 22 over the top 45 of the tea kettle and drains down into the pan 23. This is done without removing the fumigated articles and the lid is closed for one quarter of an hour or so, whereas the disinfection and deodorization is completed, 50 the emitted fumes evaporating from the clothing with great rapidity. The liquid in the pan now consists of hexamethylene-tetramin in ammonia water and this liquid is poured away and the pan 23 rinsed and 55 replaced in the container ready for the next sterilization.

While I preferably use a pan 23, it is possible to use the tea kettle 24 alone, the kettle being filled with boiling hot water, 60 but having the lid 25 turned upside down so as to form a receptacle for the formalin solution when it is poured into the tube 21. The solution is thus gathered in the inverted lid 25 and is heated directly from below by 65 the hot water in the kettle. Of course the

use of a pan is preferable, as the formalin solution is brought more closely into contact with the heater constituted by the kettle.

While I have described this apparatus as being used with a kettle full of hot water 70 and while it is preferable to pour the formalin solution over the kettle in the manner described, yet it is obvious that other disinfecting materials may be used within the drum 19 without departing from the spirit 75 of the invention. It will be seen that the chimney 20 and the drum 19 permit the vapors of the formaldehyde to pass through the clothes without the clothes coming into contact with the disinfecting solution and 80 further it will be seen that the funnel 22 permits the introduction of the formalin and the introduction later of other disinfecting materials or deodorizing materials, without removing the clothes. This device 85 has been constructed with a view to the greatest possible simplicity, both of construction and operation so that it may be used in households and so that its purchase 90 may be made possible to those even of the lowest means.

Having thus described my invention, what I claim is:—

1. A disinfecter including a container having a side wall and a bottom wall and 95 open at its top, a cover adapted to have hermetically sealed engagement with the top of the container, a drum open at its bottom and having a top, and disposed within the container, the diameter of the drum being 100 nearly that of the container, the drum having an upwardly extending perforated chimney and being itself perforated, a funnel removably disposed within the chimney and closing the upper end thereof, and a funnel 105 tube extending from the funnel downward through the chimney and discharging into the upper portion of the drum.

2. A disinfecting apparatus of the character described, comprising a container having 110 a bottom and side wall and open at the top, a lid adapted to have hermetically sealed engagement with the container, an open bottom drum removably disposed within the container and resting on the bottom thereof, 115 the drum being perforated and having a perforated chimney, a solution containing pan disposed beneath the drum and on the bottom of said container, a heating element disposed in said pan beneath the chimney 120 and within the drum, and a funnel tube disposed within the chimney and discharging against the top of the heating element and having a funnel at its upper end resting upon the walls of the chimney and when 125 in place closing the upper end of the chimney.

3. In a disinfecter of the character described, a circular container, a lid for the container, a circular drum having a perfo- 130

rated body and a perforated centrally disposed chimney, the drum having an open bottom resting upon the bottom of the container, a pan disposed on the bottom of the container and adapted to contain solution, a hot water container disposed within the pan and beneath the chimney of the drum, and a funnel tube resting at its upper end

on the chimney and having its lower end disposed over the hot water container.

10

In testimony whereof I hereunto affix my signature in the presence of two witnesses.
